UNITED STATES PATENT OFFICE.

BARTON B. WARD, OF NEW YORK, N. Y.

ELECTRIC SEARCH-LIGHT.

SPECIFICATION forming part of Letters Patent No. 449,719, dated April 7, 1891.

Application filed August 21, 1890. Serial No. 362,600. (No model.)

To all whom it may concern:

Be it known that I, BARTON B. WARD, a citizen of the Dominion of Canada, and a resident of New York, in the county of New York and State of New York, have invented a certain new and useful Electric Search-Light, of which the following is a specification.

My invention relates to apparatus commonly known as "electric search-lights," and more particularly to means for rotating or moving the lamp and reflector together to permit the beam of light to be projected in any desired direction in a vertical or horizontal plane.

15 My invention consists in the special combinations of mechanism hereinafter described, whereby the desired vertical or horizontal movement may be produced.

20 My invention consists, further, in the combination, with the mechanism for producing the horizontal movement and a mechanism for producing the vertical movement, of means for locking or unlocking the one from the other, whereby the same handle may be 25 used to turn the light in either a vertical or a horizontal plane at pleasure, as hereinafter more particularly described and claimed.

In the accompanying drawings, Figure 1 is a vertical central section of an apparatus embodying my invention. Fig. 2 is a front elevation, a part being shown in section. Fig. 3 is a cross-section through a part of the supporting-frame. Fig. 4 is a side elevation of 35 a part of the mechanism for imparting movement to the lamp and reflector in a vertical plane from the vertical rotary shaft.

30 A is a U-shaped frame or support for the lamp and reflector, which latter are mounted so as to be capable of turning in a vertical plane in said frame A to permit the beam of light to be projected at any desirable vertical angle to the horizon.

40 B is a standard or support on which frame A is properly mounted, so as to be capable of 45 turning in a horizontal plane.

45 The lamp and reflector may be mounted together in the casing C and the latter be provided with suitable pivots or bearings, as indicated at b, whereby it may turn in a vertical plane in A; or the pivots may be attached to any other frame or support common to the lamp and reflector.

D is any reflector, E the carbons of any focusing-lamp, and F the casing containing the lamp mechanism.

55

Attached to the frame A and extending down through the standard or support B and through the floor or base G is a stem or shaft H, which may be rotated by means of a wheel H² or other device for the purpose of turning 60 the frame supporting the lamp and reflector in a horizontal plane. By this means the lamp and reflector may be located on the top of a pilot or wheel house and the direction of the beam of light controlled by the pilot at 65 his station beneath.

For the purpose of turning the lamp and reflector in a vertical plane a rock-shaft or spindle I is provided, which runs down through the shaft H, and at its lower end has a handle-arm I², while at its upper end it is provided with a gear that gears with a wheel upon the horizontal shaft L, mounted in bearings L² on the frame A. The wheel M is secured to the shaft L, and a wheel N is fastened to the pivot or shaft b, carrying the lamp and reflector. The belt O connects the wheels M N.

70

75

Electrical connection with the lamp is made by sliding contacts, preferably in the form of 80 rings, carried, respectively, by the frame B and the standard or support A and resting upon one another. Preferably these rings constitute the bearings upon which the frame is supported and turned. Such contacts are 85 indicated at c c² and d d². The rings c c², of copper, brass, or other good conductor, are let into or supported upon a block of insulating material carried on top of standard B, and are connected by insulated wires or conductors running through said standard or by other means with the opposite poles of the circuit supplied from a dynamo-electric machine or other source of electric current. The rings d d² are fixed in a block of insulating 90 material at the bottom of the standard A and rest, respectively, on the rings c c². Wire connections run from rings d d² along the inner side of the frame A to the case C at or near the pivots and lead through the case or 100 its pivots to the lamp within.

By means of a catch P and connected to press-lever K, supported on I², the arm I² may be locked or unlocked from wheel H² at pleas-

ure. When locked, rotation of the arm will simply turn the two shafts together and rotate the lamp and reflector in a horizontal plane. When the two shafts are disengaged 5 from one another by pressing on K, the rotation of the arm will turn the shaft I alone and the lamp and reflector will be turned in a vertical plane. Any other desired means might be used for connecting and disconnecting the two shafts at pleasure. It will be seen 10 that by means of wheel H^2 , with notches around its entire circumference adapted to be engaged by the catch P, the operator is enabled to give the beam of light any desired 15 vertical inclination by turning shaft I, and then lock the two shafts together and rotate the lamp in a horizontal plane a whole circle, if desired, preserving the same vertical angle; or he may disengage the two shafts at any 20 time, change the vertical angle, and then lock them together and continue the horizontal rotation of the beam of light.

While I have shown a special construction 25 of device for locking the two shafts together, I do not limit myself thereto, as other means will occur to mechanics as suitable for locking the two together when desired.

In a prior application filed by me January 13, 1890, Serial No. 336,791, I have shown an 30 organization similar to that herein shown and described, but in which the devices passing down through the hollow shaft II for the purpose of tilting the lamp and reflector consist of cords passing over pulleys. The general 35 construction and organization therefore has been broadly claimed in the prior application referred to, and in my present application I confine myself to the special construction of the devices which extend through said shaft and connect to the vertically-tilting frame carrying the lamp and reflector.

What I claim as my invention is—

1. The combination, substantially as described, with the lamp and reflector and the 45 supporting-frame therefor, of the two vertical operating-shafts, one within the other, a handle secured to one of them, means for locking and unlocking the one shaft from the other at pleasure, and an intermediate gear between 50 one shaft and the lamp and reflector for causing the latter to tilt in a vertical plane when said shaft is rotated.

2. The combination, substantially as described, of the lamp and reflector pivoted on 55 a rotatable supporting-frame, a vertical shaft I, a horizontal shaft L, gearing with shaft I, a wheel M on the outer end of the shaft L, a wheel N upon the pivot or spindle carrying the lamp and reflector, and a connecting-belt between said wheels M N, as and for the 60 purpose described.

3. The combination, substantially as described, of the concentric shafts H I, a rotat-

able U-shaped frame carrying the lamp and reflector and secured to the vertical stem or 65 shaft H, a shaft I, concentric with shaft H, a horizontal shaft L, mounted on the rotatable frame and gearing with shaft I, wheels M N, secured, respectively, to the shaft L and to the horizontal spindle or pivot for the lamp 70 and reflector, and a belt connecting said wheels, as and for the purpose described.

4. In a search-light, the combination, substantially as described, of a rotatable U-shaped frame mounted on a standard or support and rotatable in a horizontal plane, a lamp and reflector pivoted to turn in a vertical plane in said U-shaped frame, a depending vertical stem H, attached to the horizontal rotatable frame and carrying an operating-wheel H^2 below the standard, an internal shaft I, connected at its upper end with mechanism for rotating the lamp and reflector in a horizontal plane, and a horizontal arm I^2 , connected to the shaft I at its lower end and 85 carrying an operating-handle, as and for the purpose described.

5. The combination, substantially as described, in a search-light, of stem H, connected to the horizontally-rotatable frame, shaft 90 I, carrying the operating-handle and connected by suitable intermediate mechanism with the vertically-rotatable lamp and reflector, an operating-handle secured to shaft I, and a lock or catch for connecting the shaft I 95 with the stem H at pleasure, as and for the purpose described.

6. The combination, in a search-light, of a rotatable frame rotatable in a horizontal plane, a lamp and reflector pivoted to turn in 100 a vertical plane in said frame, concentric operating-shafts H I, one attached to the frame directly and the other to the lamp and reflector through a suitable intermediate gearing, an operating-handle or arm attached to 105 one of the shafts, and a wheel H^2 and catch for locking the shafts together at any desired point in the rotation of the arm, as and for purpose described.

7. The combination, in an electric search-light, of a rotatable support for the lamp and reflector rotatable in a horizontal frame, an operating arm or handle connected to the mechanism for changing the vertical angle of the beam of light, and means for connecting 115 said arm or the parts attached thereto with the horizontally-rotatable support at pleasure, as and for the purpose described.

Signed at New York, in the county of New York and State of New York, this 20th day 120 of August, A. D. 1890.

BARTON B. WARD.
